[57] CLAIM

The ornamental design for a game table, as shown and described.

DESCRIPTION

FIG. 1 is a front isometric view of a game table showing my new design;

FIG. 2 is a top plan view thereof, at a reduced scale;
FIG. 3 is a rear elevational view looking from the opposite side of FIG. 1, and also at a reduced scale; and FIG. 4 is an enlarged fragmentary vertical sectional view taken substantially along the line 4—4 in FIG. 1.
